DESIGN FOR A JAR

Tito Pasta, Los Angeles, Calif.

Application November 8, 1938, Serial No. 80,951

Term of patent 14 years

To all whom it may concern:

Be it known that I, Tito Pasta, a citizen of the United States, residing at Los Angeles, in the county of Los Angeles and State of California, have invented a new, original, and ornamental Design for a Jar, of which the following is a specification, reference being had to the accompanying drawing, forming part thereof.

I claim:

The ornamental design for a jar, as shown.

TITO PASTA.
